Patented Oct. 9, 1917.

UNITED STATES PATENT OFFICE.

JACK ZATZKIN, OF JERSEY CITY, NEW JERSEY.

BED-FRAME.

1,242,509.

Specification of Letters Patent.

Patented Oct. 9, 1917.

Application filed December 20, 1915. Serial No. 67,944.

To all whom it may concern:

Be it known that I, JACK ZATZKIN, a citizen of the United States, and a resident of Jersey City, in the county of Hudson and 5 State of New Jersey, have invented certain new and useful Improvements in Bed-Frames, of which the following is a specification.

This invention relates to improvements in 10 childrens' cribs, particularly those having metallic frames, and its principal object is to provide means whereby either or both side guard frames may be automatically locked and firmly held in a raised position 15 or lowered by the release of the locking means from a single point.

Such object is attained by the novel construction and combination of parts herein-after described and shown in the accompanying 20 drawing, forming a material part of this specification, and in which:—

Figure 1 is a perspective view of a metal framed crib illustrating the application of the invention.

Fig. 2 is an enlarged fragmental, partial side elevation and sectional view showing the construction and manner of attachment of the invention, and

Fig. 3 is a fractional, sectional view showing a modified form of locking means.

In the drawing, the numeral 10 designates the posts of the crib, the same resting preferably on casters 11 in order that the crib may be readily and easily moved about.

Ornamental knobs 12 are usually supplied at the tops of the posts, having bars 14 rigidly extending between the end posts, which are also connected by lower bars 15.

Vertical bars 16 are engaged at their ends 40 with the horizontal bars forming in effect stiffening elements which also operate as guards to prevent the occupant from falling over the edge of the bed and the injury consequent thereto.

One of the sides of the crib may have 45 permanent guards consisting of a pair of horizontal bars 18 attached to the side posts and having between them a plurality of vertical bars 19, as shown on the far side of the crib indicated in Fig. 1, which is thus far of well known construction.

The improvement consists in rigidly affixing a pair of brackets 20 and 21, respectively upper and lower, to the side posts 10, 55 near the top and bottom thereof, and in

such manner that the brackets extend toward the opposite end facing each other.

In these brackets are rigidly secured vertical rails 22, tubes being preferably used, arranged to stand parallel and prevented 60 from turning by the inserted plugs 24, as shown in Fig. 2, or other equivalent means, so that the holes 25 may always be presented open toward the opposite end.

Freely slideable on the rails 22 are yokes 65 26 having sleeves 27 in which are rigidly engaged hollow bars 28, extending between opposite pairs, the bars being connected by a plurality of vertical bars 29 corresponding to the bars 19 on the opposite side of the 70 crib.

In the upper bar 28 are two slideable plugs 32 having grips 33 rigidly inserted therein and extending outward through slots 34 formed in the wall of the hollow bar 28. 75

Between the plugs 32, so as to normally press them apart, and opposing the grips 33, is a coiled push spring 35, and secured in the outer ends of the plugs are thin slideable rods 36, the same extending through the 80 sleeves 27, in which they are guided so that the ends of the rods may register with the holes 25, in the rails 22, when the side frame is raised to its full height, engaging therein by reason of the spring 35, thus locking the 85 frame in position until released by pressing the grips 33 toward each other.

In order to prevent a child occupying the crib from being able to lower the side guard or otherwise inadvertently releasing the 90 lock, a guard plate 38 is attached to the bar 28 and extended down on the inner side below the grips 34 in such manner that they can be operated only from the exterior of the crib.

In Fig. 3 a modified form of locking means is shown, in which the rails 22 are 95 perforated, as at 40, in the upper front ends in place of at the sides.

The yoke and sleeve construction remain 100 substantially the same, as does the tubular bars 42 extending therebetween. At the center of the upper bar is secured a plug 43, by the screw 44, and passing through the plug is a wire rod 45 to which is attached 105 the inner end of the conically coiled torsion spring 46, the outer end of which is secured by the screw 44.

The ends 47 of the rod 45 are bent at a right angle and screw threaded to receive 110

collars 48, after which they pass out of the tube through slots 49 formed therein and engage with handles 50 by means of which they may be rotated to an extent limited by 5 the length of the slot.

Arms 52, extend laterally from the operating handles 50 and are formed to extend so that pins 53 set therein may engage with the perforations 40 when in a locked condition.

In operation, when the guard frame is in a lowered position, and it is desired to raise and secure the same, it is only necessary to lift the frame, whereupon, when the pins 53 15 reach the level of the perforation they will be forced in by the action of the torsion spring 46.

In releasing or unlocking the frame, either of the handles 50 may be raised, clearing 20 the pin of the perforation and allowing the frame to be lowered.

As the handles extend normally downward they are not easily accessible to the crib occupant but very convenient for operation by one outside the crib.

Thus it is possible for a person to operate the locking device with one hand by a perfectly easy motion, as is also the case with the device previously described, and so far 30 as known this cannot be done with any of the arrangements in present use.

Having thus described my invention, what

I claim as new and desire to secure by Letters Patent, is:—

1. In a device of the class described, the 35 combination with a pair of vertical rails having perforations through their walls at the outer side near the top thereof, a frame slidably engaging said rails, a tubular element in said frame, a rod rotatably held in 40 said tubular element, said rod having bent ends extending outwardly through said element, operating handles on said rod, arms carried by said handles, said arms having 45 means for engagement with the mentioned 40 perforations and means for exerting a torsional effect upon said rod, handle and arms whereby the latter are normally pressed against said rails.

2. In a device of the class described, a 50 pair of spaced vertical rails, a frame slideable thereon, said frame having an upper hollow element, of a plug rigid in said element, a rod revoluble in said plug, means combined with the ends of said rod adapted 55 to engage in perforations in said rails, an operating means therefor and a torsion spring adapted to normally cause engagement between said engaging means and said rails.

In testimony whereof I have signed my name to this specification.

JACK ZATZKIN.
